CLAIM

The ornamental design for a game table, as shown and described.

DESCRIPTION

2. Game table
2.1 : Perspective
2.2 : Left
2.3 : Right
2.4 : Front
2.5 : Back
2.6 : Top
2.7 : Bottom
2.8 : Perspective
2.9 : Left
2.10 : Right
2.11 : Front
2.12 : Back
2.13 : Top
2.14 : Bottom

The broken lines shown in the figures are for the purpose of illustrating portions of the game table and form no part of the claimed design.

Figures 2.-2.7 illustrate a first configuration of the claimed design. Figures 2.8-2.14 illustrate a second configuration of the claimed design.
